CLIP REMOVING TOOL

Norman C. Woolums, 6001 7th St. S., St. Petersburg, Fla., and Ervin C. Carpenter, 8201 49th St. N., Pinellas Park, Fla.

Filed Jan. 23, 1961, Ser. No. 63,881

Term of patent 7 years

(Cl. D54—13)

Fig. 1

Fig. 2

Fig. 4

Fig. 3

FIG. 1 is a perspective view of a clip removing tool showing our new design.

FIG. 2 is a top plan view thereof.

FIG. 3 is a side elevational view thereof.

FIG. 4 is a cross-sectional view taken on the line 4—4 in the direction of the arrows, but with portions omitted for convenience of illustration.

The dominant features of our design reside in the portions shown in full lines.

We claim:

The ornamental design for a clip removing tool, as shown and described.
